ERASER FEEDING MECHANISM

Angelo Gaimari, Chicago, Ill.

Application May 8, 1939, Serial No. 272,329

2 Claims. (Cl. 120—38)

This invention relates to automatic pencils and analogous devices and has as its principal object the provision of an improved eraser feeding mechanism especially adapted for use in such devices.

More particularly stated, it is an object of the invention to provide an eraser feeding mechanism including a sleeve member threaded on its interior, a threaded rider adapted to move back and forth in the sleeve responsive to turning movement of one with respect to the other, and an elongated eraser moved by the rider.

Another object is an arrangement wherein the sleeve is adapted to be mounted on the end of an automatic pencil and the eraser is provided with configurations keying the same to a cap which turns on the sleeve, the cap being turned to effect similar movement of the eraser and the rider to cause the latter to move back and forth within the sleeve and effect advancing or retractive movement of the eraser.

Another object is the arrangement of the sleeve to turn on a pencil, the eraser member being movable back and forth within the sleeve and having a threaded rider which is held against turning in an especially constructed inner sleeve, whereby turning of the main or outer sleeve will cause the rider to move back and forth within the same and the inner sleeve to retract or advance the eraser.

Other objects, advantages and economies peculiar to the invention reside in certain details of construction, as well as the arrangement and mode of operation of the parts of the illustrative arrangements depicted herein in the annexed drawing, in which:

Fig. 1 is a top plan view of the eraser attachment;

Fig. 2 is a fragmentary vertical section through the feeding attachment mounted on a pencil, looking in the direction of line 2—2 of Fig. 1;

Fig. 3 is a horizontal section to enlarged scale along line 3—3 of Fig. 2;

Fig. 4 is a fragmentary vertical section through the rider, looking in the direction of line 4—4 of Fig. 3;

Fig. 5 is a fragmentary vertical section through the combined feeding mechanism and pencil in a modified arrangement;

Fig. 6 is a vertical section of the inner sleeve member looking in the direction of line 6—6 of Fig. 5;

Fig. 7 is a horizontal section through the device of Fig. 5 as seen in the direction of line 7—7 of Fig. 6;

Fig. 8 is a fragmentary vertical section through the rider of Fig. 5, looking in the direction of line 8—8 thereof;

Fig. 9 is a horizontal section through the rider, looking down along line 9—9 of Fig. 8;

Fig. 10 is a horizontal section, looking up in the direction of line 10—10 of Fig. 5.

As shown in Figs. 2 and 4, one form of feeding attachment includes an outer barrel or sleeve 15 provided with threading 16 on its interior and having its lower end threaded onto a threaded coupling shoulder 17 at the upper end of a pencil barrel 18 so that the sleeve is held in substantially immovable relationship with the pencil. A sleeve-like rider 19 is provided with threading 16 engageable with the threading 16 on the interior of the sleeve, and an elongated eraser member 21 has its lower end securely fitted into the rider, in the present instance by being threaded into the same in engagement with the inner configurations of the threading 20. As a result of this arrangement, the eraser and rider are secured together for joint turning movement, and when the rider is turned it rides along the threading in the sleeve and moves the eraser in and out, depending upon the direction of turning effort.

Means for turning the rider includes an end sleeve or cap 22 fitted over the upper end of the main barrel or sleeve 15 so as to turn on the latter and having an open end portion 23 through which the eraser projects. The eraser and turning cap are keyed to turn in unison as a result of the provision of keying formations in the form of substantially flat surfaces 24 with intervening longitudinal ribs 25 extending along the length of the eraser. Only one such surface or rib is necessary, but it is preferable in the illustrative embodiment to make the eraser of hexagonal cross section and to form the opening 23 correspondingly.

Thus, when the end cap 22 is turned in either direction, it is coupled with the eraser by the interlocking engagement of the parts 24 or 25 on the eraser with the correspondingly shaped parts of the opening 23, notwithstanding the fact that the eraser is free to slide in and out of the cap. As a result of the turning of the eraser, the rider 19 is likewise turned and caused to move up and down within the barrel as a result of the engagement of the threading 20 thereon with the threading 16 on the inside of the barrel sleeve.

In the modified arrangement of Fig. 5, the main sleeve or barrel 30 is telescoped onto a

reduced shoulder 31 at the upper end of a pencil 32, and the barrel is free to turn relative to the pencil, the barrel being provided with internal threading 33 as in the case of the device of Fig. 2. 5 There is provided a second or inner sleeve 34 (Fig. 6) having an integral flange part 35 which rests on the upper end portion of the barrel 30, while the lower end portion of the inner sleeve is slotted longitudinally as at 36 so as to fit in frictional 10 engagement into the bore at the upper end of the pencil barrel 32, this bore suitably shaped so as to prevent the inner sleeve from turning relative to the pencil.

An elongated eraser 37 is clamped at its lower 15 end (Fig. 8) into a cup-shaped rider 38, this rider having opposite radially extensive ears or wings 39 in which are cut suitably pitched teeth 40 for threadable engagement with the internal threading 33 in the main barrel. The eraser and rider 20 are fitted into the second or inner sleeve, the latter being provided with opposite longitudinally extensive slots 41 in which the threaded or toothed wings 39 work as the rider moves back and forth responsive to turning of the main or outer barrel 25 30. A suitable end cap 42 is fitted onto the upper end of the barrel for removal when it is desired to use the eraser. Having removed the cap 42, the operator holds the pencil barrel 32 in one hand and turns the eraser barrel 30 with the 30 other hand, thus working the rider in one direction or the other to advance or retract the eraser as needed.

The objects and advantages of the invention 35 may be accomplished in modified forms of the specific construction described herein for purposes of illustration, and the invention is not to be limited to such specific forms except as may be provided in the appended claims.

Having thus described my invention, what I 40 claim as new and desire to protect by Letters Patent is:

1. An eraser feeding mechanism comprising an

internally threaded sleeve adapted to be mounted on the end of a pencil or the like, a threaded rider arranged for movement back and forth in the sleeve between the ends thereof responsive to turning movement of the rider with respect to 5 the sleeve, an elongated eraser element secured at one of its ends in said rider for movement with the latter in a direction into and out of said sleeve, and a second sleeve member mounted for turning movement at an end of said first-men- 10 tioned sleeve and having an opening through which said eraser element projects, said eraser element and said second sleeve being provided with mutually engaging parts keying the same together for joint turning movement such that turning of said second sleeve relative to said first-mentioned sleeve will effect similar movement of the eraser element and rider with a consequent advancing or retracting movement of the eraser element into or out of said first-mentioned sleeve. 20

2. An eraser feeding mechanism comprising an internally threaded sleeve having an operating sleeve fitted onto an end thereof for rotative movement thereabout, the said operating sleeve having an opened end in alignment with the bore 25 of said first-mentioned sleeve, a threaded rider disposed in said first-mentioned sleeve for movement back and forth therein responsive to relative rotative movement between the sleeve and rider, and an elongated eraser member secured to 30 said rider for rotative movement therewith and arranged to project through said open end of the operating sleeve and being slidable relative to the latter, and means on said operating sleeve engaging said eraser member to prevent rotation 35 of the latter with respect to the operating sleeve 31 whereby turning movement of the operating sleeve will effect similar movement of the eraser member and said rider with a consequent movement of the eraser member in a direction into and out 40 of said open end of the operating sleeve.

ANGELO GAIMARI.
